(57) **CLAIM**

The ornamental design for a piston for compressor, as shown and described.

DESCRIPTION

FIG. 1 is a front perspective view of a piston for compressor showing our new design;

FIG. 2 is a rear perspective view thereof;

FIG. 3 is a front view thereof, the rear view being an identical image of FIG. 3;

FIG. 4 is a top plan view thereof;

FIG. 5 is a bottom plan view thereof;

FIG. 6 is a right side elevational view thereof, the left side elevational view being an identical image of FIG. 6;

FIG. 7 is a cross-sectional view taken along line 7—7 of FIG. 5;

FIG. 8 is a cross-sectional view taken along line 8—8 of FIG. 5; and,

FIG. 9 is a cross-sectional view taken along line 9—9 of FIG. 5.
